UNITED STATES PATENT OFFICE

JOHN H. BARR, OF NEW YORK, N. Y., ASSIGNEE TO REMINGTON TYPEWRITER COMPANY, OF ILION, NEW YORK, A CORPORATION OF NEW YORK.

TYPE-WRITING MACHINE.

1,217,898.

Specification of Letters Patent.

Patented Mar. 6, 1917.

Application filed April 20, 1916. Serial No. 92,429.

To all whom it may concern:

Be it known that I, JOHN H. BARR, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to the tabulator mechanism of such machines.

15 My invention has for its principal object to provide improved means for setting and restoring the tabulator or column stops and especially for setting and restoring said stops by means of keys in the keyboard of the machine.

20 The key operated restoring or clearing means which I have provided, is capable of clearing the tabulator entirely, that is to say, restoring all of the set tabulator stops, and it is also capable of restoring any selected set stop.

25 My stop set mechanism is simple in construction and is readily adaptable to existing machines, or to certain existing machines, by utilizing as part of the mechanism features already present in said machines.

30 To the above and other ends which will hereinafter appear, my invention consists in certain features of construction and combinations and arrangements of parts, all of which will be fully set forth herein and particularly pointed out in the claims.

35 One embodiment of my invention is illustrated in the accompanying drawings, in which—

40 Figure 1 is a front-to-rear vertical sectional view of a typewriting machine having my invention embodied therein.

45 Fig. 2 is a fragmentary elevation of part of Fig. 1 but showing the "clear" key in depressed position in full lines and the "set" key in depressed position in broken lines.

50 Fig. 3 is a fragmentary front elevation of the column stop bar with some of the stops thereon.

55 Fig. 4 is a side view of the same with the bar in section.

Fig. 5 is a rear elevation of the machine with parts in section and parts broken away.

Fig. 6 is a bottom view of the same.

55 Fig. 7 is a side elevation showing the stop

setting and restoring mechanism in normal position, and with most of said mechanism in fore and aft vertical section.

Fig. 8 is a rear elevation of parts of the same but with some of the parts sectioned away, the section being taken about on the line 8—8 of Fig. 7.

Fig. 9 is a plan view of this portion of the mechanism with parts in section about on the line 9—9 of Fig. 7.

Fig. 10 is a plan view of these parts in section on the line 10—10 of Fig. 7.

Fig. 11 is a view similar to Fig. 7 but showing the mechanism in the operated position it occupies when the stop-set key is depressed.

Fig. 12 is a view similar to Fig. 7 but showing the mechanism in the position it occupies when the "clear" key is depressed.

In the drawings, parts have been broken away or shown in section, or omitted entirely, as has been found convenient.

I have shown my invention applied to a Smith Premier No. 10 typewriter. The main frame of this machine comprises side plates 80 11 which include posts 12 and on which is supported the top plate 13. Said side plates are connected together by said top plate, by a back frame bar 14, a keyboard plate 15, a front plate 16, and other parts. Standards 17 rising from the top plate 13, support a stationary carriage rail 18 on which a carriage 20 is adapted to travel through the usual ball bearing connection. Said carriage has the usual platen frame 21 mounted therein and in which the platen 22 is mounted.

90 The carriage is fed toward the left by means of a spring 23 coiled in a drum 24, and said spring is connected with a large gear wheel 25 which meshes with a rack 26 on the carriage. Another large gear wheel 27 meshes with said rack and both the gear wheels 27 and 25 and the spring drum 24 have an arbor 28. The gear 27 meshes with a pinion 30 formed as shown in Fig. 1 with ratchet clutch teeth on its rear face, and said clutch teeth intermesh with similar teeth on a splined clutch member 31 which is pressed by a light spring 32 toward the clutch pinion 30. The clutch member 31 is splined on a shaft 33, which shaft drives the escapement wheel of the machine. Said wheel and the balance of the escapement mechanism are not shown herein.

95 The shaft 33 is journaled at its for-

100 in Fig. 1 with ratchet clutch teeth on its rear face, and said clutch teeth intermesh with similar teeth on a splined clutch member 31 which is pressed by a light spring 32 toward the clutch pinion 30. The clutch member 31 is splined on a shaft 33, which shaft drives the escapement wheel of the machine. Said wheel and the balance of the escapement mechanism are not shown herein.

105 The shaft 33 is journaled at its for-

110 in Fig. 1 with ratchet clutch teeth on its rear face, and said clutch teeth intermesh with similar teeth on a splined clutch member 31 which is pressed by a light spring 32 toward the clutch pinion 30. The clutch member 31 is splined on a shaft 33, which shaft drives the escapement wheel of the machine. Said wheel and the balance of the escapement mechanism are not shown herein.

115 The shaft 33 is journaled at its for-

ward end in a frame plate (not shown) and at its rear end on a pivot screw 34 threaded through an ear of a frame plate 35 constituting part of the casing which carries the 5 carriage driving and escapement mechanism. The clutch member 31 is adapted to be moved toward the rear of the machine away from the clutch member 30 by means of a rocking member 36 pivoted at 37 and 38 10 in ears of the plate 35. Said rocking member 36 has at its upper end a roller 40 that bears against a bar 41 constituting part of a bail having arms 42 pivoted to the carriage at 43 and constituting part of the ordinary carriage release mechanism of the Smith Premier machine. Each of the arms 42 has a forwardly extending arm, not here shown, but having a key on its forward end; and the construction is such that when said 15 key is depressed the bar 41 is moved toward the rear of the machine, the member 36 is rocked about its pivots, and the clutch member 31 is moved to its disconnecting position.

The machine is equipped with various 20 paper feed devices not necessary here to be described but comprising paper fingers 44, Fig. 5, and a paper table 45.

The machine also comprises margin stop and line lock mechanism including a toothed 25 bar 46 at the back of the machine mounted on arms 47 which arms are rigidly mounted on and hang down from a rock shaft 48, which at its ends is journaled in a carriage 20. On the bar 46 are mounted margin 30 stop devices 50 of the sort commonly employed in the Smith Premier machine. The margin stop frame 46-47 can be swung up to the position shown in dotted lines in Fig. 1. The margin stops coöperate with certain 35 devices 51, Fig. 1, not necessary here to be described.

Some parts of the tabulator mechanism shown in the drawings are like, and they may, if desired, be identical with, parts 40 heretofore commonly used in the Smith Premier typewriter. Said mechanism includes one or more key-operated stops, the machine shown in the drawings being 45 equipped with a series of denominational 50 stop bars 52 extending up at the back of the machine at their upper ends, and at their lower ends extending down in front of the back plate or bar 14. Said stop bars are pivoted at 53 to a series of nested bails, 55 each comprising an arm 54, a cross-bar 55 and another arm 56. The arms 54 and 56 are pivoted on a horizontal rod 57 mounted in a frame 58 which is secured, as by screws 60, to the back bar 14. Each of the arms 60 56 is formed or provided with a depending branch 61 to which is pivoted the rear end of a long push rod 62, which at its forward end carries a key 63. Said keys pass through a guide plate 64 which is suitably mounted 65 on the front bar 16 and has an indicating

plate 65 on which are imprinted the various denominational designations. Each of the push rods 62 is shown provided with a restoring spring 66 connected at one end to a collar 67 on the push rod and at the other end to a cross bar 68 mounted in the base of the machine. The construction is such that if one of the keys 63 be pushed toward the rear the corresponding yoke frame or bail 61, 56, 55, 54 will be rocked and one of the denominational stop bars 52 will be elevated. It will be perceived that the nested bails serve to reverse the order of the tabulator keys as compared with that of the tabulator stops. Without this reversal of order, the keys at the front of the machine would be arranged in the reverse of their natural order, as they are in many denominational tabulators. It will also be perceived that each of said bails is in effect a bell-crank having a depending arm 61 connected with a push rod 62 and a rearwardly extending arm 54 to which a stop bar 52 is pivoted.

In order to operate the carriage release, each of the arms 56 is prolonged toward the rear of the machine as shown, and a universal bar 70 lies over the rear ends of these prolongations in such position that it will be moved upward whenever one of the tabulator keys is operated. As here shown, said universal bar consists of a plate of sheet metal having its forward edge bent down to overlie the arms 56 and said plate secured as by screws 71 to a hub or arm 72 rigidly mounted on a rock shaft 73, which rock shaft is journaled in ears 74 of the frame bar 14. Said hub or arm 72 is shown formed with a depending arm 75 with an adjustable stop screw 76 mounted therein, 100 for contacting with the frame bar 14 to limit the downward motion of the universal bar. Said universal bar is moved downward by means of a compression spring 77, Fig. 1, coiled about a post 78 depending 105 from the frame bar 14.

The carriage release mechanism connected with the universal bar 70, comprises a lever 80 pivoted at 81 to an ear 82 of the frame plate 14 and at its upper end lying in front 110 of the carriage release device 36 hereinbefore described, so that, if the upper end of the lever 80 be rocked toward the rear of the machine the clutch 31 will be opened. This lever in the Smith Premier machine 115 is connected with the universal bar through the instrumentality of a second lever 83 pivoted at 84 to the side of the lever 80 and having a forked lower end which straddles a pin 85, Figs. 5 and 6, projecting from an 120 arm 86 mounted on the rock shaft 73. The lever 83 is normally prevented from turning about its pivot 84 by means of a pin or rod 87 which projects through a hole in the lever 80 and has its end lying in the path 125

of the lever 83. The whole construction is such that when the universal bar 70 is rocked the lever 80 is rocked through the devices shown, to release the carriage; but if the rod 5 87 be pulled a short distance into the lever 80, it will let go of the lever 83, thus, in effect, breaking the lever 80, so that the carriage will be restored to the control of its escapement, notwithstanding the tabulator 10 key is still held in its operated position. Said rod is pulled toward the right in the operation of reverse tabulating, as will be described hereinafter.

The return motion of the keys under the 15 impulse of their springs 66, is limited by a cross bar 88, Figs. 1 and 6, mounted on the underside of the frame 58 by means of screws 90 passing through slots to allow adjustment of said cross bar 88.

20 The column stops 91 are mounted on a square bar 92 having in its upper and under sides slots a letter space distance apart after the ordinary fashion of column stop bars, and said bar is equipped with a full 25 set of column stops one for each letter space position. The bar 92 is secured by screws 93 to the under ends of arms 94 which at their upper ends are loosely mounted on the rock shaft 48 hereinbefore described as supporting the margin stop bar 46; which bar 46, it will be recalled, can be turned to the position shown in dotted lines in Fig. 1 for the purpose of setting the margin stops.

In the Smith Premier No. 10 machine as 30 heretofore constructed the column stop bar of the tabulator was mounted in much the same relative position with respect to the margin stop bar as is shown in the present drawings; but both bars were mounted on 35 the same arms of the shaft 48 and both the column stop bar and the margin stop bar could be turned up together to a position convenient for setting the stops. In the present case, however, the tabulator column 40 stops are set by keys in the keyboard and the column stop bar is therefore removed from the swinging frame and is mounted on the separate arms 94. These arms are rendered incapable of swinging and at the same 45 time are rendered adjustable in a front and back direction by mounting them loosely instead of rigidly on the shaft 48 and by providing each of them with two adjusting screws 95, 96, the first threaded through the 50 arm 94 and bearing against the carriage rail at the back, and the second threaded through a horizontal branch 97, Fig. 1, of the arm 94 and bearing against the upper surface of the carriage rail. By loosening 55 one of these screws and tightening the other the bar 92 can be adjusted front or back, and when both screws are tight the bar is held 60 against front and back motion. The screws 95 and 96 can be provided with lock nuts 98.

65 In order to provide for a fine adjustment

of the bar 92 lengthwise, the screws 93 can be made to pass through slots in said bar 92 and one end of said bar 92 bears against the head of a screw 100, Fig. 5, which screw is threaded into the enlarged lower end of 70 the arm 94. The bar is adjusted with precision by the screw 100 after which the screws 93 are tightened. If at any time it is necessary to remove the bar 92 it can be replaced with precision by merely pushing 75 it up against the screw 100 before tightening the screws 93.

The upper ends of the denominational stops 52 are guided in a suitably slotted plate 101 mounted on the upper end of a 80 frame 102, which is pivoted on a rod 103, Fig. 7, in a bracket 104, which depends from the top plate 13 to which, as here shown, it is secured by screws 105. In the Smith Premier machine as heretofore manufactured, the frame 102 is pivoted in this manner in order to secure a column jumping or column selecting feature, all as fully set forth in the patent to Ford 945,159, dated Jan. 24, 1910.

85 The pivoted frame 102, both in the present construction and also in the ordinary Smith Premier machine, is controlled in its pivotal movement by an arm 106 forming part of said frame and extending downward 90 below the pivot rod 103 into the base of the machine. I connect a link 107 to the lower end of said arm by a pivot 108, and said link extends toward the front of the machine beneath the keyboard, its forward 95 end being pivoted to a three-armed lever 110 by a pivot screw 111. The link 107 is pivoted to a downwardly extending arm of said lever 110, and said lever also has a forwardly extending arm to which is pivoted the stem 112 of a stop set key 113. Said lever also has a rearwardly extending arm to which is pivoted the stem 114 of a "clear" 100 key 115. The lever 110 is pivoted at 116 to a plate 117 which is secured, as by screws 118, to one of the side plates 11. A yielding 105 detent 120 is pivoted to the plate 117 at 121, and it has a spring 122 connected therewith and pulling the forward end of said detent 115 downward. At its forward end said detent 120 has a roller 123 which engages a notch or 120 depression in the center of the upper surface of the lever and holds said lever in its normal middle position shown in Fig. 1. If the key 115 be depressed the lever will be 125 rocked as shown in full lines in Fig. 2, the roller 123 riding up on the forward arm of the lever 110 and tending to restore the lever to normal position. If the key 113 be depressed the lever will be rocked in the opposite direction as shown by broken lines in Fig. 2, and then said key is released the parts will be restored to their normal, middle position by the detent.

125 When the key 113 is depressed the link 130

107 and arm 106 are moved toward the rear of the machine and the frame 102 which guides the denomination stops 52 will be moved toward the front of the machine as shown in Fig. 11; whereas if the key 115 be depressed the link 107 and arm 106 will be moved toward the front of the machine and the frame 102 will be moved toward the rear of the machine as shown in Fig. 12.

10 In the Smith Premier machine as heretofore manufactured there has been a frame corresponding to the frame 102 and an arm corresponding to the arm 106, said frame and arm together constituting a lever of the first order; and said arm and frame have been normally held in the middle position and have been capable of swinging to either of two forward positions or to either of two rear positions of said frame for the purpose of effecting denomination selection after the manner set forth in the Ford patent hereinbefore referred to and in the patent to A. T. Brown, No. 927,414, dated Oct. 19, 1909. In the form of the invention shown in the drawing, I utilize this frame for the purpose of setting the column stops and resetting or restoring them to normal position; but for some of the purposes of my invention, another lever or other device can be used and the key-operated stops can have a fixed guide. Each of the column stops 91 is mounted on the bar 92 in a manner which will be understood from Figs. 3 and 4 where it will be seen that each of said stops consists of a bifurcated piece of sheet metal slipped on to the bar 92 from the rear, the slot between the two arms of the stop being of sufficient length to allow the stop to occupy the normal or inoperative position shown in full lines in Fig. 4, and also to allow of said stop being pushed toward the front of the machine to the operative position shown in broken lines in Fig. 4. Each column stop has a lug or downward prolongation 124, which, when said column stop is in its forward, or operative position, is adapted to be engaged by any of the stops 52 that is operated by its key; but when the column stop is in its rear position, said lug is out of reach of the stops 52. Each of said column stops has a spring detent 125 mounted thereon by means of a rivet 126. As here shown the upper branch of this detent is formed with an abrupt shoulder 127 which, by engagement with one of the teeth of the rack bar 92, prevents the stop from being slipped entirely off the bar; and the lower arm of each of said detents is formed with a tooth 128 having inclined sides so that when the stop is in the full-line position of Fig. 4 said tooth engages in a notch on the under side of one of the teeth of the bar 92 and when said stop is pushed to the broken line position in Fig. 4 said tooth 128 engaging the corner of one

of the teeth of the rack bar holds the column stop in its operative position. Said column stop can be pushed from one of its positions to the other, however, because the tooth 128, having inclined sides, will yield to the exertion of any considerable force. Any column stop can be removed from the bar at any time by swinging the upper arm of the detent upward enough for the shoulder 127 to be lifted clear of the rack bar.

In order to set any desired one of the series of column stops, I mount an arm 130 on the frame 102, the position of which arm will be understood by comparing Figs. 1 and 5. When the frame 102 is moved toward the front of the machine by depressing the key 113 this arm 130 engages one of the column stops 91 near to the denomination stop of lowest order. The construction is such that if the typewriter carriage be moved to any given letter space position and the key 113 be then operated, a column stop will be set in such position that an operation of the denomination stop of lowest order, that is to say, the one corresponding to the decimal point, at any time thereafter will cause the typewriter carriage to be arrested at that letter space position. The arm 130 can be mounted on the frame 102 in any suitable manner. In the present instance said arm is made of sheet metal and it includes a part 131 (Fig. 7) lying flat against the web of the frame 102 to which it is secured by screws 132, the operative part of the arm being bent off to the rear from that part of the arm which is secured to the rocking frame.

In order to restore said column stops or any of them, I have provided a wiper 133. This stands just in front of the line of travel 105 of the lower branches of the several column stops 91 in such position that if it be moved toward the rear of the machine to the position shown in Fig. 12 by the depression of the key 115, any column stop that is standing behind it will be forced to its ineffective position. Said wiper is, as seen in plan view in Fig. 9, elongated in a right and left-hand direction and made with its sides inclined so as to act as a cam with the result 110 that if said wiper be held in its operated position shown in Fig. 12 and the carriage be moved throughout its entire travel in either direction all of the column stops that are in set position will be restored by a camming action to their ineffective positions.

The wiper 133 could be mounted directly on the frame 102 if desired but if so it would be swung forward of its normal position when a column stop was being set 125 by an operation of the key 113. This would be inconvenient because the column stop bar is directly behind the depending flange of the top plate 13; and to allow the wiper to swing forward of its normal position 126

would involve a considerable cutting away of said flange and also perhaps some cutting away of the bracket 104. I have accordingly so mounted the wiper that when the key 113 is depressed said wiper does not move forward with the frame 102 but remains in its normal position as will be perceived by an inspection of Fig. 11. To this end said wiper is mounted on a separately pivoted frame or arm 134, the wiper itself being directly mounted on a plate 135 (Fig. 8) which plate is secured by screws 136 to said arm 134. Said arm or pivoted device 134 is journaled on a rod 137 mounted in ears 138 of the bracket 104. The device 134 is held in its rear position by a plate spring 140 secured by a screw 141 to the bracket 104.

In order to move the pivoted device 134 and wiper 133 toward the rear when the key 115 is operated, a pin 142 is secured in and projects upward from a guide arm 143 consisting of a bracket on or a branch of the frame 102. This guide arm extends backward from said frame into a notch or space between two lugs 144 depending from the flange of the top plate 13; and said guide arm constitutes a part of the ordinary Smith Premier construction. It will be perceived that when the key 115 is depressed and the frame 102 rocked toward the rear, the pin 142 carries the wiper 133 rearward with it as shown in Fig. 12; but when said frame is swung toward the front by the key 113, the pin 142 moves away from the wiper 133 and leaves said wiper in its normal position, as shown in Fig. 11.

In operation it will be perceived that any column stop can be set in the manner hereinbefore described; and if then the operator perceives that he has set the wrong stop he can immediately restore it by an operation of the key 115, after which he can move the carriage to the correct position and set the correct stop. Also, if a number of stops have been set and it is desired to restore any one of them independently of the rest, this can be done by operating the tabulator key corresponding to the decimal point so as to bring that particular column stop into register with the wiper 133, and then operating the key 115. If it is desired to restore all of the column stops, this can be done by depressing and holding down the key 115 and moving the carriage from one end of its travel to the other.

It will be perceived that this stop-set mechanism has the advantage over most others that both the "set" key and the "clear" key are in the keyboard of the machine where they can be operated with a maximum of convenience and also that the entire mechanism is quite simple and that use has been made for some of the operat-

ing parts, of mechanism already in the manufactured machine so that this key set tabulator can be very readily incorporated into existing machines. Moreover, my mechanism is available as an alternative construction so that in the process of manufacture machines can be equipped either with the former column-selecting tabulator or with my stop-set tabulator at the option of the purchaser.

My mechanism does not interfere with other functions of the tabulator. For example, the Smith Premier tabulator as heretofore manufactured is adapted for reverse tabulating, that is to say, for using the tabulator stops to arrest the carriage on the return travel of said carriage toward the right as well as in its travel toward the left. In this operation it is necessary to compensate for the difference in position of arrest of the carriage due to the fact that when the carriage is traveling toward the left the column stop 91 encounters the left-hand face of a stop 52 whereas when the carriage is traveling toward the right the column stop encounters the right-hand face of said stop. In the Smith Premier machine this compensation is effected by allowing the frame 102 to move a suitable distance toward the right in reverse tabulating. To this end the rod 102 is tight in its bearing in the bracket 104 and the two arms of the frame 102 are pivotally mounted on said rod but the spacing of said arms, as shown in Fig. 8, is such as to allow the frame 102 to slide lengthwise of the rod. In order to hold said frame in its normal left-hand position, or in its right-hand position as seen from the rear in Fig. 8, part of the hub of the frame 102 is chambered out to accommodate a compression spring 145 and the end of the rod 104 is formed with an elongated head 146; and the spring 145 is compressed between said head 146 and the shoulder formed by the bottom of the chambered out part of the hub so that the spring tends to move the frame 102 toward the right in Fig. 8 or toward the operator's left. The motion of the frame 102 in a right and left direction is limited by the guide arm 143 as will be understood from Fig. 8 where it will be seen that this arm is normally pressed against the right-hand one of the lugs 144 but that there is space for it to move a little to the left before it strikes the left-hand one of said lugs.

The rod 87 in the base of the machine (Fig. 5) is pivoted at one end at 147 to an ear 148 of the arm 106, the construction being such that when the frame 102 and arm 106 are moved toward the operator's right, that is to say, toward the left in Fig. 5, the rod 87 will also be moved in the same direction and the end of said rod will become disengaged from the lever 83, thus in effect

breaking the lever 80 and allowing the clutch member 31 to be restored to its connection with the clutch member 30, thus instantly restoring the carriage to the control of its escapement. These are old features of the Smith Premier machine and they are mentioned here merely to call attention to the fact that my mechanism does not interfere with them.

10. The machine is equipped with ribbon spools 150 one of which is mounted on a puppet 151 which passes through the bracket 104 so that it appears, for example, in Fig. 7.

15. Various changes can be made in the details of construction and arrangement without departing from my invention.

What I claim as new and desire to secure by Letters Patent, is:—

20. 1. In a typewriting machine and in tabulating mechanism, the combination with a carriage and a series of settable stops, of a lever up-standing at the back of the machine and extending into the base of the 25 machine, keys in the keyboard of the machine for swinging said lever in two directions from normal position, means operated by said lever when swung in one of said directions for setting one of said stops, and 30 restoring means operated by said lever when swung in the other direction.

2. In a typewriting machine and in tabulating mechanism, the combination with a carriage and a series of settable column 35 stops, of an upstanding lever of the first order extending into the base of the machine, a link connected with the lower end of said lever and extending to the key-board of the machine, two keys in said keyboard 40 for moving said link in opposite directions from a normal position, means whereby said lever when swung in one direction sets one of said stops, and means whereby said lever when swung in the other direction can 45 restore said stops.

3. In a typewriting machine and in tabulating mechanism, the combination with a carriage and a series of settable column stops, of a lever, means whereby said lever 50 when swung in one direction from normal position can set one of said stops, restoring means operated by said lever when swung in the other direction, two keys in the key-board, a lever having two arms to which 55 said keys are respectively connected so that one of said keys swings said lever in one direction, and the other in the other, and connections from the said key-operated lever to the first mentioned lever.

60. 4. In a typewriting machine and in tabulating mechanism, the combination with a carriage and a series of settable column stops, of one or more key operated stops for 65 coöperation with said column stops, a movable guide for said coöperating stop or stops,

means for moving said guide, and a column-stop-restoring device operated by said guide.

5. In a typewriting machine and in tabulating mechanism, the combination with a carriage and a series of settable column 70 stops, of one or more key-operated stops for coöperation with said column stops, a movable guide for said coöperating stop or stops, means for moving said guide, a column-stop-setting device operated by said guide, and a 75 column-stop-restoring device operated by said guide.

6. In a typewriting machine and in tabulating mechanism, the combination with a carriage and a series of settable column 80 stops, of one or more key-operated stops for coöperation with said column stops, a movable guide for said key-operated stop or stops, and a device mounted on said movable 85 guide for setting said column stops.

7. In a typewriting machine and in tabulating mechanism, the combination with a carriage and a series of settable column 90 stops, of one or more key-operated stops for coöperation with said column stop, a movable guide for said key-operated stop or stops, and a device operated by said movable 95 guide for restoring said column stops.

8. In a typewriting machine and in tabulating mechanism, the combination with a 100 carriage and a series of settable column stops, of a frame movable in two directions from normal position, a stop-set device on said frame and operative to set one of said column stops when the frame is moved in one direction, a restoring device independently pivoted to the framework, and means whereby said restoring device is operated by the motion of said frame in the opposite direction but inoperative on said restoring device when the frame is moved in stop-setting 105 direction.

9. In a typewriting machine and in tabulating mechanism, the combination with a carriage and a series of settable column 110 stops, of one or more key-operated stops, the lever 102, 106 extending into the lower part of the machine, the setting and restoring devices operated by said lever, the link 107, extending to the front of the machine, 115 and the means for moving said link in opposition directions.

10. In a typewriting machine and in tabulating mechanism, the combination of a stop carrier, a series of stops carried thereby and 120 each settable front and back to operative and inoperative positions, an upright lever of the first order having a stop-setting device at the upper end thereof operative by a motion of said lever in the direction from normal position, a stop-restoring device operative by a movement of said lever in the opposite direction, and means in the keyboard of the machine for swinging said lever in both said directions.

- 1,000,000
11. In a typewriting machine and in tabulating mechanism, the combination of a stop carrier, a series of stops carried thereby and each settable to operative and inoperative positions, an upright lever having a stop-setting device at the upper end thereof operative by a motion of said lever in one direction from normal position, a stop-restoring device operative by a movement of said lever in the opposite direction, a link extending from the lower end of said lever forward to the keyboard of the machine, and means for moving said link in both directions from normal position.
12. In a typewriting machine and in tabulating mechanism, the combination of a stop carrier, a series of stops carried thereby and each settable to operative and inoperative position, an upright-lever having a stop-setting device at the upper end thereof and constituting a part of said lever and brought by a motion of said lever in one direction from normal position into operative engagement with one of said stops, a stop-restoring device operative by a movement of said lever in the opposite direction, and means at the keyboard of the machine for swinging said lever in both said directions.
13. In a typewriting machine and in tabulating mechanism, the combination of a stop carrier, a series of stops carried thereby and each settable to operative and inoperative position, a lever having one arm thereof
- constituting a stop-setting device which is brought into operation by a movement of 35 said lever in one direction from normal position, a stop-restoring device movably mounted in the stationary framework of the machine, means whereby a movement of said lever in the opposite direction operates said 40 stop-restoring device, and means for swinging said lever in both said directions.
14. In a typewriting machine and in tabulating mechanism, the combination of a three-armed lever at the keyboard of the machine, two keys mounted respectively on two of the arms of said lever, a link connected with the third arm on said lever and extending therefrom toward the back of the machine, said link being pulled toward the 45 front of the machine by a depression of one of said keys and pushed toward the back of the machine by a depression of the other key, a series of settable tabulator stops, a 50 stop-setting device operated by one of the movements of said link, and a stop-restoring device operated by the other movement of said link.

Signed at the borough of Manhattan, city of New York, in the county of New York 60 and State of New York, this 19th day of April, A. D. 1916.

JOHN H. BARR.
